David Gibbs,
BY G. H. Strong,
ATTORNEY

UNITED STATES PATENT OFFICE.

DAVID GIBBS, OF SAN FRANCISCO, CALIFORNIA.

FLUSH-OUT.

1,120,925.

Specification of Letters Patent. Patented Dec. 15, 1914.

Application filed June 11, 1913. Serial No. 773,029.

To all whom it may concern:

Be it known that I, DAVID GIBBS, a citizen of the United States, residing in the city and county of San Francisco and State of California, have invented new and useful Improvements in Flush-Outs, of which the following is a specification.

This invention relates to a flushing valve for water-closet tanks.

10 It is the object of this invention to provide a flushing valve of the loose ball type, with means for lifting the ball from its seat from its underside, which is so constructed as to obviate disposing the valve operating mechanism within the tank.

15 A further object is to provide a simple and efficient flushing valve which is durable and not liable to get out of order.

The invention primarily resides in a tank 20 having a sloping bottom leading to a flush-out pipe, a valve seat at the mouth of the flush-out pipe, a loose ball adapted to rest on said seat to prevent the discharge of liquid from the tank, and means disposed 25 in the flush-out pipe operable by a hand lever exterior thereof for lifting the ball from its seat.

The invention further consists of the parts and the construction and combination of 30 parts as hereinafter more fully described and claimed, having reference to the accompanying drawing, in which—

Figure 1 is a vertical section of one form of the invention. Fig. 2 is a section in elevation on the line *a—a* of Fig. 1. Fig. 3 is a vertical section of a modified form of the invention. Fig. 4 is a horizontal section and elevation on the line *b—b* of Fig. 3. Fig. 5 is a horizontal section on the line 40 *c—c* of Fig. 1.

In the drawings, A represents the bottom of a tank or reservoir of any suitable construction; the bottom A being inclined downwardly toward its center. Mounted on the bottom A at its lowest point is a tubular member 2, which is threaded on its exterior and adapted to be engaged by a threaded sleeve or union 3 on a nipple 4 threaded in the upper end of the elbow 5. The elbow 5 is connected at its lower end with a bowl or other structure, not shown. The member 2, nipple 4, and elbow 5 constitute a flush-out pipe leading from the bottom A of a tank to a suitable point of discharge.

Interposed between the ends of the member 2 and the nipple 4 is a spider or ring 6, which is supported on the upper end of the nipple 4 and is held in place by a washer 7 clamped between the ends of the member 2 and the nipple 4 by means of the union 3. 55 The ring 6 is formed with transverse ribs which support a central perforated member 9 which serves as a guide and support for a vertically disposed rod 10. The rod 10 is threaded at its upper end and is screwed 60 into a collar 11 on which a ring 12 is supported on outwardly and upwardly extending arms or standards 13 on the collar 11. The ring 12 is designed to normally contact the underside of a loose ball 14 seated 65 on the upper open end of the member 2, the ball 14 forming a valve and the member 2 a seat therefor.

In the form of the invention shown in Figs. 1 and 2, the bar 10 is formed with radial teeth 15, on one of its vertical edges, which teeth mesh with a toothed segment 16 mounted on a rock-shaft 17 extending across the interior of the elbow 5 and passing through a stuffing-box 18 in the latter. The bar 10 70 is retained in mesh with the segment 16 by means of a guide yoke 19 secured to the interior of the elbow 5; the bar 10 passing between forked members on the guide yoke 19, as shown in Fig. 1.

In the form of the invention shown in Figs. 3 and 4, the lower end of the bar 10 is pivotally connected to an arm 16' secured to the shaft 17. Wound on the bar 10, and bearing between the guide member 9 and a pin 20 on the bar 10, is a spring 21 which acts to normally retain the bar 10 in its lowermost position. The shaft 17 is provided with a hand lever 22, exterior of the elbow 5, by means of which the shaft 17 85 may be rocked.

When the ball 14 is disposed on its seat and the tank is filled with water, or other liquid, the ball will be held in its seated position by the weight of the liquid thereabove. When it is desired to discharge the liquid from the tank, the ball 14 is lifted from its seat by operating the hand lever 22 in such a manner as to raise the rod 10 in opposition to the spring 21, thus causing 90 the ring 12 to engage the underside of the ball 14 and lift it clear of its seat. When 95 this occurs the ball, by reason of its being

constructed in such manner as to float, will rise to the surface of the liquid in the tank, thereby leaving the upper end of the flush-out open so that the contents of the tank 5 will be rapidly discharged therefrom. Upon releasing the handle 22 the spring 21 will operate to restore the rod 10 to its normal lowermost position. When the tank is empty the ball 14 will be caused to roll 10 down the inclined bottom A into position on the valve seat member 2, thus closing communication between the tank and flush-out pipe so that the latter may be refilled. By thus constructing the valve operating 15 mechanism and disposing it within the flush-out pipe, and by forming the tank with a sloping bottom A, the use of cages for guiding and directing the ball 14 and the valve operating mechanism within the tank is dis- 20 pensed with.

In some instances the handle 22 may be weighted sufficiently to restore the bar 10 to its normal position on releasing the handle, in which event the spring 21 may be dis- 25 pensed with.

Having thus described my invention, what

I claim and desire to secure by Letters Patent is—

In combination with a tank having a discharge and a tube therein, a spider connected 30 to the tube, a rod slideable in the spider, a ball, a ring to support the ball, an interiorly threaded collar having its base seating on top of the spider, spaced divergent arms connected to the collar and ring, a rod slideable through the spider and threadedly connected to said collar, a spring connected to and surrounding the rod and abutting the lower side of the spider, a pivoted upwardly movable handle to actuate the rod and means 35 to operate the rod from the handle, said handle being limited in its downward movement by engagement of the collar with the upper face of the spider.

In testimony whereof I have hereunto set 40 my hand in the presence of two subscribing witnesses.

DAVID GIBBS.
